UNITED STATES PATENT OFFICE.

LARRY E. GOMMER, OF PONTIAC, MICHIGAN.

TURBINE.

Application filed October 2, 1923. Serial No. 666,156.

To all whom it may concern:

Be it known that I, LARRY E. GOMMER, a citizen of the United States, and a resident of Pontiac, in the county of Oakland 5 and State of Michigan, have invented a new and Improved Turbine, of which the following is a full, clear, and exact description.

The present invention relates to new and useful improvements in engines, and it pertains more particularly to engines of the 10 rotary turbine type.

It is one of the objects of the invention to provide a new and improved rotor structure for turbine engines.

15 It is a further object of the invention to provide a new and improved structure of turbine engines in which there are a plurality of impelling elements simultaneously operated.

20 It is a further object of the invention to provide a new and improved control for turbine engines, which control serves to regulate the pressure of steam introduced to the rotor of the turbine.

25 It is a further object of the invention to provide a new and improved mechanism whereby the impelling fluid introduced to the turbine may be maintained within the limits of a predetermined pressure.

30 With the above and other objects in view, reference is had to the accompanying drawings, in which—

Figure 1 is a transverse vertical section of a turbine constructed in accordance with 35 the present invention;

Fig. 2 is a view in elevation of the turbine rotor;

Fig. 3 is a longitudinal vertical sectional view of the turbine taken on the line 3—3 of 40 Fig. 1;

Fig. 4 is a view in end elevation of the rotor showing the rotor shaft in cross section.

Referring more specifically to the drawings, the turbine comprises a base 5 and a housing which is cylindrical in form, the lower portion 6 of the housing being formed integral with the base 5. The other half of the housing is designated by the reference numeral 7, and is secured to the portion 6 thereof by means of bolts or the like, 8.

The reference numeral 9 designates an exhaust, of which there are three in the 55 present instance, and leading from each of the exhausts 9 there is a pipe 10 connected

to a pipe 11 by a coupling 12, which pipe 11 is connected to an exhaust manifold 13.

The upper portion 7 of the housing is provided with a plurality of intakes 14, 60 connected by means of a pipe 15, to a three-way coupling 16, and by means of the pipes 17 and 18 and a coupling 19, the three-way coupling 16 communicates with the intake manifold 20. Secured to the leg 21 of the 65 three-way coupling 16, there is a pipe 22, and secured to the pipe 22, there is a valve 23, the seat of which is designated by the reference numeral 24. The reference numeral 25 designates a valve member provided 70 with a stem 26 surrounded by a spring 27, the upper end of which spring engaging the inner end wall of a cap 28 screw-threaded, as at 29, into the body of the valve 23. The lower end of the spring 27 engages the valve 75 member 25. Leading from the valve 23, there is a pipe 30, connected by means of a coupling 31 and a pipe 32 to a secondary exhaust manifold 33. The operation of the foregoing mechanism will be hereinafter described.

The housing members 6 and 7 are formed with recesses 35, and mounted in such recesses 35 are bearings 36 of the anti-friction type. At one end the housing is extended, 85 as at 37, and mounted in the bearings 36 there is a shaft 38, such shaft having an extension 39 mounted in the extension 37 of the housing. The shaft 38 has spaced threaded sections 40, and mounted within 90 the threaded sections 40 are members 41, which form end plates of the rotor. The rotor comprises a cylindrical member 42, and the end plates are secured to the cylindrical member 42 by bolts, screws, or the like, 43. The cylindrical member and the end plates 41 are retained in adjusted position upon the shaft 38 by nuts or the like, 44.

The two members 5 and 6 of the housing are provided with alined channels 45, and 100 the cylindrical member is formed with channeled flanges or rims 46 adapted to project inwardly of the channels 45 in the members 5 and 6 of the housing, and at the point of juncture of the cylindrical member with the members of the housing, there are contact elements 47, set in recesses in the housing members and the cylindrical member of the rotor.

Mounted in each of the channeled flanges 110 46 of the rotor are two sectional annular members 50, and such sectional annular

members 50 are secured in position by bolts, or the like, 51, which pass through the cylindrical member of the rotor, as shown in Fig. 1. These sectional annular members 5 are formed with radial projections 52 spaced with respect to one another to provide intervening pockets 53, and the rotor is of such construction that the projections will pass in the presence of the intake passage 14 as the rotor travels in a rotary path.

Leading through the upper member 6 of the housing there are a plurality of passages 55, and each of the passages 55 has communication with a pet cock 56, the purpose 15 of which will be hereinafter described.

The operation of the device is as follows: The elements forming the rotor being arranged in parallel, steam is admitted by way of the intake port 14 to the interior of 20 the housing, and in the presence of the projections 52 of the sectional annular members 50 of the rotor and imparts rotary movement to the rotor, the same exhausting through the exhaust passage 9.

In order to regulate or predetermine the pressure at which the steam is admitted to 25 the rotor, the valve 23 heretofore mentioned is employed, and by screwing the cap 28 until it places the spring 27 under the desired tension, the valve 25 will be held to 30 its seat until the predetermined pressure of fluid has been exceeded. For example, if the cap is screwed and the spring 27 is placed under compression to a predetermined point, say to permit steam of sixty 35 pounds to enter the turbine, immediately the steam pressure exceeds sixty pounds, the valve 25 will open and reduce the pressure allowing the predetermined pressure to 40 enter the housing of the turbine.

In order to determine the condition of the packing, it is only necessary to open the pet cocks 56. The presence of fluid in the

space with which the pet cocks communicate, indicates a leaking condition of said packing.

By this construction it is apparent that the valve 23 serves to regulate the pressure of the steam or other fluid employed to operate the turbine, and through this medium 50 serves to maintain the steam of the turbine constant, all within certain predetermined limits.

I claim:

1. In a turbine, a rotor assemblage, said 55 rotor assemblage comprising a shaft, a plurality of plates carried by the shaft, a cylindrical member surrounding said shaft and supported by said plates, and sectional annular members secured to the outer surface of said cylindrical member, said sectional annular members being formed with 60 pockets.

2. In a turbine, a rotor, said rotor comprising a shaft, a cylindrical member carried thereby, a plurality of integral spaced flanges formed in the periphery of said cylindrical member to provide spaced channels, sectional annular members formed on their outer periphery with projections, said sectional annular members adapted to be received within said channels, and bolts passing through the walls of said cylindrical member into engagement with the sectional annular members to secure them in their 75 respective channels.

3. In a turbine, a rotor comprising a cylindrical member provided with spaced peripheral channels, and pocket members mounted in said channels, said pocket members comprising sectional annular members adapted to embrace said cylindrical member and occupy a position within the channels 80 thereof.

LARRY E. GOMMER.
